UNITED STATES PATENT OFFICE.

GOTTFRIED SCHICK, OF TAMPA, KANSAS.

DESIGN FOR A PLATE-RACK.

45,022.

Specification for Design.

Patented Dec. 9, 1913.

Application filed September 29, 1913. Serial No. 792,523. Term of patent 14 years.

To all whom it may concern:

Be it known that I, GOTTFRIED SCHICK, a citizen of the United States, residing at Tampa, in the county of Marion and State of Kansas, have invented a new, original, and ornamental Design for a Plate-Rack, of which the following is a specification, reference being had to the accompanying drawing, forming part thereof.

Figure 1 is a front elevation of a plate

rack showing my ornamental design, and Fig. 2 is an end view thereof.

I claim:

The ornamental design for a plate rack, as shown.

GOTTFRIED SCHICK.

Witnesses:

P. H. MEEHAN,
MARIE STEMMERMAN.
